DEVICE FOR ROWING A BOAT WITH
ONE HAND

Forrest C. Mollenhauer, Center Point, Iowa

Application January 7, 1950, Serial No. 137,469

6 Claims. (Cl. 9—24)

1

This invention relates to a rowing device and more particularly to device for rowing a boat with one hand.

A device which permits a person to operate two oars of a rowboat and control maneuvering thereof by using one hand only is of great use and advantage to a disabled person who has lost the use of one of his arms, and also to fishermen who desire to cast or troll for fish with one hand while rowing and maneuvering the boat with the other hand.

Thus, one of the objects of this invention is to provide a novel and improved device which will enable a person to operate the two oars of a rowboat and properly control and maneuver the same by using only one hand.

Another object of this invention is to provide a device for rowing a boat with one hand and which device permits retaining the "feel" of all of the movement of the oars and imparts said feel to the operator.

A further object of this invention is to provide a device which will enable a person to operate the two oars of a rowboat by using only one hand and which will also permit use of but a single oar for purposes of manipulating and steering the boat.

A still further object of this invention is to provide a novel and improved oar for use with a device for rowing a boat with one hand and which may also be used as a conventional oar in the normal manner.

And still a further object of this invention is to provide a device for rowing a boat with one hand which will automatically position the hand grip centrally during the rowing operation without fixing the oars to the carlocks.

Further objects and advantages of this invention will become apparent as the following description proceeds and the features of novelty which characterize this invention will be pointed out with particularity in the claims annexed to and forming part of this specification.

A preferred embodiment of the invention is shown in the accompanying drawing, in which—

Figure 1 is a plan view of a fragmentary portion of a boat where the oars are mounted, showing the novel device for rowing the boat with one hand. The one hand rowing device is shown in two positions, the center position, shown in dot and dash outline, in which the oars extend oppositely and in alignment, and a displaced position through which the oars pass during a typical rowing operation.

Figure 2 is a transverse, sectional view of the

2

boat and showing the one hand rowing device, in two positions. In the full line position both oars are shown as they would be used in a normal rowing operation. The second position, in which the hand grip and one oar are shown in dot and dash outline, shows the manner in which the oars are positioned for using but a single oar in rowing.

Figure 3 is a top plan view of the oars and hand grip assembly showing the construction details more clearly.

Figure 4 is a side view of the oar and hand grip of Figure 3, with portions in section to show details of construction.

15 Figure 5 is a face view of the carlock, with the oar in section, taken on the line 5—5 of Figure 2.

Figure 6 is an exploded view of an oar which may be used as a normal oar and which may be 20 adapted, by removal of the hand grip portion, for use with the one hand rowing device.

Referring to Figures 1 and 2 there is shown a boat 11 whose sides 12 have mounted exteriorly thereon plates 13 adapted to receive pins 15 of 25 carlocks 14. Plates 13 are secured to the boat's sides 12 by means of screws 13a as shown in Figure 5. A device for rowing a boat with one hand is indicated generally by numeral 16 and comprises a pair of oars 17 and a hand grip 18. A pair of universal joints 19 are secured to and interconnect the ends of the hand grip 18 and the pair of oars 17.

Referring to Figures 3, 4 and 5, the oars 17 are shown comprising an oar shank 20 and an 35 oar blade 21. The oar blade 21 extends from one end of oar shank 20 and the hand grip 18 is connected to the other end of oar shank 20. The inboard end or hand grip end of the oar shank 20 has a tapped hole 22 therein for receiving a threaded connecting member. As shown in Figures 3 and 4, said connecting member is a 40 threaded stud 23, constituting a part of the universal joint assembly 19, and connects hand grip 18 to an oar shank 20.

The oar shank 20 in regular oars is generally cylindrical in shape but in the present construction the oar shank 20 has a linear portion 24 which is non-circular in cross section, as seen in Figure 5. This portion 24, as seen in Figure 5, is of an oblong-cylindric form with a pair of flat faces. The handle end 20a of the oar shank 20 is cylindrical and is the portion that has the tapped hole 22 therein for receiving said threaded connecting member. This handle end 20a of the oar shank 20 is located inboard of

the oar lock 14 and extends over a relatively small portion of the length of the oar shank, as compared to the length of the non-cylindrical portion 24 of the oar shank.

The oarlock 14, as shown in Figures 3 and 5, comprises an upright U-shaped portion 25 and a pivot pin 15 extending downward from the lower portion of the U-shaped portion 25. The arms 26 of the U-shaped portion 25 bound therebetween a recess 27 which, as shown, is of greater depth than width. The width of recess 27 is slightly greater than the width of the oblong-cylindric portion 24 of the oar shank 20. The oblong-cylindric portion 24 of oar shank 20 is slidably positioned in the recess 27. The lower surface 28 of recess 27 is rounded so that the area of contact surface between oarlock 14 and the oar 17 is small, thus eliminating excess friction.

The arms 26 of oarlock 14 cooperate with the flat faces of the oblong-cylindric portion 24 of oar shank 20 to prevent rotation of oar 17 in the oarlock recess 27. The oblong-cylindric portion 24 of oar shank 20 is so positioned in the oarlock recess 27 that the oar blade 21 is always in operative rowing attitude. As shown in Figures 3 and 5, the maximum dimension of the oblong-cylindric portion 24 is substantially vertical and lies substantially in the same plane as does the oar blade 21.

A chain 29 is secured at one end to oarlock 14 and at the other end to a point on the oar shank 20 remote with respect to the oarlock. This chain 29 lies outboard of the boat and acts to restrict the outboard motion of the oar 17 through the oarlock 14 in a manner as will be described below. These chains 29 are detachably connected to both the oarlock 14 and the oar 17 in any well known manner.

As shown in Figure 6, the oars as indicated at 17a may also be used as normal oars. Handles 30, having threaded connecting studs 23a may be secured to oar shanks 20 to produce a conventional oar. Regular oarlocks, not shown, having a circular ring for carrying the oar may also be used. The oblong-cylindric portion 24 of oar shank 20 will act as a full cylinder in such an oarlock since the maximum dimension of portion 24 is the same as the diameter of the full cylinder. Appropriate detachable means (not shown) may also be provided for limiting the motion of the oar 17a in the regular oarlock.

Operation

When the oars 17 are in a straight opposed position, shown by the dot and dash line view in Figure 1, the chains 29 are extended to their greatest extent and limit further outward movement of the oars. At any other position which the oars will assume during the rowing operation, one or both of chains 29 will be in a lesser extended position and will therefore be slack.

During the rowing operation, as the rower moves the hand grip 18 from the dot and dash line position in Figure 1 to the solid line position in Figure 1, the oars 17 will bear against the arms 26 of the oarlocks 14 and provide pivots for the oars 17. Simultaneously the oars will slide in recesses 27, moving through recesses 27 in an inboard direction. As the oars 17 move inboard the ends of each chain 29 will move closer to each other and the chains will become slack.

As the rower moves the oars 17 through the rowing cycle, the oars will pass from the solid line position in Figure 1 through the dot and dash

line position in Figure 1. As the oars 17 are oscillated about the straight opposed position shown by the dot-dash line view in Figure 1, the oars 17 will reciprocatingly slide in recesses 27 of oarlocks 14 in an inboard and outboard direction. The greatest outboard extension of the oars 17 will take place when the oars 17 are in the straight opposed position.

As described above, the chains 29 are extended to their greatest extent when the oars are in the straight opposed position. Since in every rowing operation the oars 17 are oscillated through, or in the vicinity of, this straight opposed position it will be seen that these chains 29 automatically serve to centrally position the entire rowing device 16 during the rowing operation. Such central positioning is highly desirable since the efficiency of a rowing operation is largely dependent upon the uniformity of stroke of both oars.

When the chains 29 are disconnected, the cylindrical portion 20a of the oar shank, inboard of the oarlock 14, cooperates with the arms 26 of oarlock 14 to prevent the oar 17 from sliding outboard through recess 27. Thus it can be seen that even with the chains 29 detached the entire rowing device 16 will still be positioned to permit a rowing operation.

To operate a single oar at a time, the rowing device 16 is manipulated substantially into a position as shown in dot and dash lines in Figure 2. The hand grip 18 is turned to a substantially upright position. The outboard movement of the oar that is being used is restricted by the chain 29. The oar that is not being used slides inboard through recess 27 of oarlock 14. It will be noted that the inboard movement of the unused oar brings the center of gravity of the unused oar closer to the oarlock 14. With the lower surface 28 which bounds recess 27, acting as a fulcrum point, the raising of the unused oar from the water is made with less effort on the part of the rower when the center of gravity of the unused oar is closer to the oarlock.

While there has been shown and described a particular embodiment of this invention, it will be obvious to those skilled in the art that various changes and modifications may be made therein without departing from the invention and, therefore, it is intended in the appended claims to cover all such changes and modifications as fall within the true spirit and scope of the invention.

What I claim as new and desire to secure by Letters Patent of the United States is:

1. A device for rowing a boat with one hand comprising a pair of oarlocks mounted to pivot about spaced upright axes, each oarlock having a recess therein of non-circular cross section, an oar for each oarlock, each oar having an elongated oar shank extending through the recess in the oarlock with one portion of the oar disposed inboard of the oarlock and another portion of the oar disposed outboard of the oarlock, said oar shank and the portion of the oarlock which bounds said oarlock recess having cooperating portions which permit sliding longitudinal movement of the oar shank within the oarlock recess, said cooperating portions of the oar shank and oarlock being operative to substantially prevent rotation of the oar shank in the oarlock recess, and a hand grip connecting the inboard ends of said oars.

2. A device for rowing a boat with one hand comprising a pair of oarlocks mounted to pivot about spaced upright axes, each oarlock having a recess therein of non-circular cross section, an

oar for each oarlock, each oar having an elongated oar shank extending through the recess in the oarlock with one portion of the oar disposed inboard of the oarlock and another portion of the oar disposed outboard of the oarlock, said oar shank and the portion of the oarlock which bounds said oarlock recess having cooperating portions which permit sliding longitudinal movement of the oar shank within the oarlock recess, said cooperating portions of the oar shank and oarlock being operative to substantially prevent rotation of the oar shank in the oarlock recess, means operatively associated with the oars and the oarlocks for limiting longitudinal movement of the oars through the oarlocks in outboard directions, and a hand grip connecting the inboard ends of said oars.

3. A device for rowing a boat with one hand comprising a pair of oarlocks mounted to pivot about spaced upright axes, each oarlock having a recess therein of non-circular cross section, an oar for each oarlock, each oar having an elongated oar shank extending through the recess in the oarlock with one portion of the oar disposed inboard of the oarlock and another portion of the oar disposed outboard of the oarlock, said oar shank and the portion of the oarlock which bounds said oarlock recess having cooperating portions which permit sliding longitudinal movement of the oar shank within the oarlock recess, said cooperating portions of the oar shank and oarlock being operative to substantially prevent rotation of the oar shank in the oarlock recess, a flexible member of a predetermined length connecting said portion of the oar which is disposed outboard of the oarlock to the associate oarlock, said flexible member being operative to limit the longitudinal movement of the oar through the oarlock in the outboard direction, and a hand grip connecting the inboard ends of said oars.

4. A device for rowing a boat with one hand comprising a pair of oarlocks mounted to pivot about spaced upright axes, each oarlock having a recess therein of non-circular cross section, an oar for each oarlock, each oar having an elongated oar shank extending through the recess in the oarlock with one portion of the oar disposed inboard of the oarlock and another portion of the oar disposed outboard of the oarlock, said oar shank and the portion of the oarlock which bounds said oarlock recess having cooperating portions which permit sliding longitudinal movement of the oar shank within the oarlock recess, said cooperating portions of the oar shank and oarlock being operative to substantially prevent rotation of the oar shank in the oarlock recess, an enlargement of the inboard portion of the oar for engaging portions of the oarlock to limit movement of the oar in an outboard direction through the oarlock, and a hand grip connecting the inboard ends of said oars.

5. A device for rowing a boat with one hand

comprising a pair of oarlocks mounted to pivot about spaced upright axes, each oarlock having a recess therein of non-circular cross section, an oar for each oarlock, each oar having an elongated oar shank extending through the recess in the oarlock with one portion of the oar disposed inboard of the oarlock and another portion of the oar disposed outboard of the oarlock, said oar shank and the portion of the oarlock which bounds said oarlock recess having cooperating portions which permit sliding longitudinal movement of the oar shank within the oarlock recess, said cooperating portions of the oar shank and oarlock being operative to substantially prevent rotation of the oar shank in the oarlock recess, a hand grip, and universal joints connecting said hand grip to the inboard ends of the oars.

6. A device for rowing a boat with one hand comprising a pair of oarlocks mounted to pivot about spaced upright axes, each oarlock having a recess therein of non-circular cross section, the recess in the oarlock having a greater depth than width, an oar for each oarlock, each oar having an elongated oar shank extending through the recess in the oarlock with one portion of the oar shank disposed inboard of the oarlock and another portion of the oar shank disposed outboard of the oarlock, the cross section of the oar shank being non-circular, the maximum width of said car shank cross section being less than the width of the oarlock recess, the maximum height of the oar shank cross section being greater than the width of the oarlock recess, said relative dimensions of the oar shank and oarlock defining cooperating portions of the oar shank and oarlocks which permit sliding longitudinal movement of the oar shank within the oarlock recess, said cooperating portions being operative to prevent rotation of the oar shank in the oarlock recess, and a hand grip connecting the inboard ends of the oars.

FORREST C. MOLLENHAUER.
